Primary Examiner — Nathaniel D. Buckner(74) *Attorney, Agent, or Firm* — Scully, Scott, Murphy & Presser, P.C.(57) **CLAIM**

The ornamental design for part of lathe, as shown and described.

DESCRIPTION

FIG. 1 is a perspective view of a part of a lathe showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the part of lathe shown in broken lines shown in the figures attached hereto form no part of the claimed design.
